UNITED STATES PATENT OFFICE.

JACQUES ROUSSO, OF CHICAGO, ILLINOIS.

COUNTING MECHANISM.

1,329,433.

Specification of Letters Patent. Patented Feb. 3, 1920.

Application filed April 20, 1916. Serial No. 92,396.

To all whom it may concern:

Be it known that I, JACQUES Roussou, a citizen of the United States, and a resident of the city of Chicago, county of Cook, and 5 State of Illinois, have invented certain new and useful Improvements in Counting Mechanisms, of which the following is a specification.

My invention relates to improvements in 10 counting mechanisms and has for its object the provision of improved mechanism of this character, especially adapted for counting perforated towels, of simple construction and efficient in operation.

15 The invention consists in the combinations and arrangements of parts hereinafter described and claimed.

The invention will be best understood by 20 reference to the accompanying drawings forming a part of this specification, and in which,

Figure 1 is a side view of a construction embodying my invention shown partially in section with portions broken away,

25 Fig. 2, a view similar to Fig. 1 taken at right angles thereto,

Fig. 3, a top plan view of the device shown in position of use,

Fig. 4, a detail section of registering 30 mechanism employed in the construction, and

Fig. 5, a plan view of a portion of a perforated towel.

The preferred form of construction as 35 illustrated in the drawings comprises a supporting plate 6 adapted to be secured to the top of a table or the like 7, with a portion projecting over the edge of said table. The plate 6 is provided in its projecting portion with a signal or sight-opening 8 and a supporting casing 9 is secured to the under-side of said plate adjacent the edge of the table. A signal arm 10 is pivotally mounted in casing 9 and is provided at one 40 end with a signal plate or button 11 co-operating with the opening 8. The other end of the signal arm 10 is bifurcated to form two arms 12 and 13 partially embracing a ratchet wheel 14 pivotally mounted in casing 45 9. Ratchet wheel 14 is provided on one side, the rear side, as shown in Fig. 1, with a laterally extending pin 15 arranged to engage arm 12 and rock the signal arm 10 on its pivot to withdraw the signal plate 11. 50 Ratchet wheel 14 is provided on one side, the rear side, as shown in Fig. 1, with a laterally extending pin 15 arranged to engage arm 12 and rock the signal arm 10 on its pivot to withdraw the signal plate 11. 55

against the resistance of a spring 16. A spring held trigger 17 is arranged to automatically engage arm 13 and lock the signal arm 10 in its withdrawn position. Another pin 18 projects laterally from the other or front side of ratchet wheel 14 in position to engage trigger 17 and release arm 10 as the ratchet wheel revolves, the pin 15 being set angularly to the rear of pin 18. A spring held roller 19 rolls upon the periphery of ratchet wheel 14 engaging the teeth thereof to prevent retrograde movement. By this arrangement it will be observed that as ratchet wheel 14 revolves, pin 18 will first engage the trigger 17 and release the signal arm. 70 Continuation of the revolution of the ratchet wheel 14 brings pin 15 into engagement with arm 12 to withdraw the signal arm, which is almost immediately latched in its withdrawn position by latch 17. 75

Coöperating with the ratchet wheel 14 is a pawl 20 pivotally mounted on the free end of the swinging lever 21 and provided with an arm 22 engaged jointly with lever 21 by spring 23. A hollow detachable towel 80 guide 24 is arranged on plate 6 and provided with a laterally extending yieldable member 25 operably connected with a plunger 26 set over the lever 21. In operation towels 27 are provided with gromets 28 85 which are passed successively downwardly over guide 24 operating member 25 each time, thus depressing lever 21 and operating ratchet 14 through one step of its movement as will be readily understood. When a pre- 90 determined number of towels have been thus placed on the guide, the signal plate 11 will be operated giving the notice thereof. The specific form of arrangements of the parts constitutes a simple and efficient one for the 95 purpose. The guide post 24 is notched at one side only, as at 24' to receive the retaining latch 24"; and this latch may be raised to permit withdrawal of the guide by merely rotating the latter on its vertical axis. 100

While I have illustrated and described the preferred form of construction for carrying my invention into effect, this is capable of variation and modification without departing from the spirit of the invention. I, 105 therefore, do not wish to be limited to the precise details of the construction set forth, but desire to avail myself of such variations and modifications as come within the scope of the appended claims. 110

Having described my invention what I claim as new and desire to secure by Letters Patent is:

1. A device of the character described comprising a support; a registering ratchet wheel on said support; a signal member bifurcated to embrace said ratchet wheel; pins projecting from opposite sides of said ratchet wheel and arranged to operate said signal member upon completing the registration of a predetermined number; and means for operating said ratchet wheel, substantially as described.
2. A device of the character described comprising a support; a registering ratchet wheel on said support; a signal member bifurcated to embrace said ratchet wheel; pins projecting from opposite sides of said ratchet wheel and arranged with one angularly in advance of the other and arranged to operate said signal member upon completing the registration of a predetermined number; and means for operating said ratchet wheel, substantially as described.
3. A device of the character described comprising a registering ratchet wheel; a signal arm in operative relation with said ratchet; a spring normally holding said arm in operative position; a trigger automatically engaging and holding said signal in inoperative position; a pin on one side of said ratchet arranged to engage said arm and set it in inoperative position; and a pin on the other side of said ratchet set angularly in front of said first mentioned pin

and arranged to engage and release said trigger upon completing the registration of a predetermined number, substantially as described.

4. A device of the character described comprising a supporting plate arranged to be secured to a table or the like to project over the edge thereof, there being a signal opening in the projecting portion of said plate; a casing secured to the under-side of the projecting portion of said plate; a registering ratchet wheel in said casing; a spring held signal arm pivotally mounted in said casing and bifurcated at one end to embrace the said ratchet wheel; a signal plate on the other end of said arm coöperating with said opening; a pin on one side of said ratchet wheel engaging one bifurcation of said arm to move said signal plate away from operative relation with said opening; a spring held trigger arranged to automatically engage the other bifurcation of said arm and hold said signal plate out of signaling relation with said opening; and a pin on the other side of said ratchet arranged to engage said trigger and release said arm upon completing the registration of a predetermined number, substantially as described.

In testimony whereof I have signed by name to this specification in the presence of two subscribing witnesses.

JACQUES ROUSSO.
